UNITED STATES PATENT OFFICE.

GILBERT L. CROWELL, JR., OF ARLINGTON, NEW JERSEY.

DESIGN FOR A HANDLE FOR SPOONS, FORKS, OR SIMILAR ARTICLES.

No. 87,563.

Specification for Design.

Patented Sept. 26, 1905.

Application filed March 11, 1904. Serial No. 197,717. Term of patent 14 years.

To all whom it may concern:

Be it known that I, GILBERT L. CROWELL, Jr., a citizen of the United States, residing at Arlington, county of Hudson, and State of New Jersey, have invented a new, original, and ornamental Design for Handles for Spoons, Forks, or Similar Articles, of which the following is a specification, reference being had to the accompanying drawing, which illustrates the design.

The figure is an elevation showing the front or obverse side of a spoon embodying my design.

I claim—

The ornamental design for a handle for a spoon, fork or similar article, as shown.
